CLAIM

An ornamental design for the feline pet care vessel as shown and described.

DESCRIPTION

FIG. 1 is a perspective view of the feline pet care vessel. FIG. 2 is an alternative perspective view of the feline pet care vessel; and,

FIG. 3 is a back view of the feline pet care vessel. The broken lines in FIGS. 1 and 2 depict panel breakaway facilitating scoring that forms part of the claimed design. The bottom of the feline pet care vessel is flat and is devoid of surface ornamentation.
